UNITED STATES PATENT OFFICE.

MAURICE WELSH AND ISADORE PAUL, OF CHICAGO, ILLINOIS.

RAZOR-BLADE HOLDER.

1,120,350.

Specification of Letters Patent.

Patented Dec. 8, 1914.

Application filed April 30, 1914. Serial No. 835,390.

To all whom it may concern:

Be it known that we, MAURICE WELSH, a citizen of the United States, and ISADORE PAUL, a subject of the Czar of Russia, and residents of the city of Chicago, county of Cook, and State of Illinois, have invented certain new and useful Improvements in Razor-Blade Holders, of which the following is a specification.

10 Our invention relates to razor blade holders and the object of our improvement is the provision of a simple and efficient holder adapted for use in sharpening safety razor blades.

15 A further object is the provision of a device of this character which may be adjusted to hold blades of different sizes and shapes.

Other objects will appear hereinafter.

With these objects in view our invention 20 consists in the combinations and arrangements of parts hereinafter described and claimed.

The invention will be best understood by reference to the accompanying drawing 25 forming a part of this specification, and in which—

Figure 1 is a side view of a holder embodying our invention, Fig. 2 is a view showing the spring clamp removed and one of 30 the handles moved on its pivotal joint, Fig. 3 is a longitudinal section of the device, and Fig. 4 is a transverse section taken on line 4—4 in Fig. 1.

The preferred form of construction as 35 illustrated in the drawing comprises two hollow handles 5 and 6, pivoted together on a pin 7 and provided with a member 8 spacing the sides of handles 5 and 6 apart and preventing movement toward each other during 40 their pivotal movements. On the corresponding end of handles 5 and 6 are jaws 9 and 10. The jaws 9 and 10 are provided with grooves 11 extending longitudinally thereof and in registration with each other.

45 Formed on jaw 9 in its groove 11 is a stationary blade holding stud 12 provided with lips 13 adapted to facilitate holding a razor blade 14 in position during adjusting the device and fixing the blade therein.

50 Formed in handle 5 is a frame 15, said frame being substantially U-shaped and provided with perforations therein. A plunger 16 is slidably mounted in said perforations and extended into grooves 11 of jaw 9. On 55 the extended end of said plunger 16 is a blade holding stud 17. Said stud 17 is also

provided with lips 18 adapted to facilitate holding a razor blade during the operation of adjusting the same to the device. In frame 15 is a leaf spring 19 engaging plunger 16 and adapted to frictionally lock the latter in its different positions.

The formation of grooves 11 in jaws 9 and 10 provide outwardly projecting beads on said jaws and a substantially U-shaped spring clamp 20 is provided with corresponding grooves adapted to fit the beads of said jaws and hold said spring in position on said jaws. The spring clamp 20 is provided to clamp the jaws 9 and 10 tightly against blade 14 to hold the latter in operative condition. In use when edge 21 of blade 14 has been sharpened the clamp 20 is reversed so that it uncovers edge 22 of said blade to permit sharpening of the latter. 75 This position of spring clamp 20 is indicated by dotted lines in Fig. 4.

In use a razor blade is placed on jaw 9 with the perforation or notch of such blade engaging stud 12. The plunger 16 is then 80 moved until stud 17 engages a suitable portion of the blade 14 to hold such blade. The handle 5 and jaw 6 are moved until jaw 10 registers with jaw 9 and the spring clamp 20 inserted over said jaws to hold the latter 85 in operative condition. When the blade is thus locked in the device such blade is strapped on a hone or strop in the manner ordinarily employed in honing or sharpening an old fashioned razor. It will be understood that upon movement of plunger 16 and stud 17 that a variety of shapes and sizes of blades may be held in the device.

While we have illustrated and described the preferred form of construction for carrying our invention into effect, this is capable of variation and modification without departing from the spirit of the invention. We, therefore, do not wish to be limited to the precise details of construction set forth, 100 but desire to avail ourselves of such variations and modifications as come within the scope of the appended claims.

Having described our invention what we claim as new and desire to secure by Letters Patent is:

1. A razor blade holder comprising a pair of handles pivoted together; a pair of jaws on said handles; a stationary blade holding stud on one of said jaws; an adjustable 110 blade holding stud on one of said jaws cooperating with said stationary stud; and a

spring clamp holding said jaws in operative condition, substantially as described.

2. A razor blade holder comprising a pair of handles pivoted together; a pair of jaws on said handles, there being registering grooves in said jaws; a stationary blade holding stud carried by one of said jaws in the groove therein and extending into the groove in said other jaw; an adjustable blade holding stud slidably mounted in the groove of one of said jaws and extending into the groove of said other jaw; and a spring clamp holding said jaws in operative condition, substantially as described.

3. A razor blade holder comprising a pair of handles; a pair of coöperating jaws carried by said handles, there being registering grooves in said jaws; a stationary blade holding stud in one of said grooves; a plunger slidably mounted in one of said handles and extending into the groove of the jaw carried by such handle; a blade holding stud on the end of said plunger in said groove, each of said studs extending from the groove in one jaw to the groove in said other jaw; and a spring clamp clamping said jaws in operative condition, substantially as described.

4. A razor blade holder comprising a pair of handles; a pair of coöperating jaws carried by said handles, there being registering grooves in said jaws; a stationary blade holding stud in one of said grooves; a plunger slidably mounted in one of said handles

and extending into the groove of the jaw 35 carried by such handle; a blade holding stud on the end of said plunger in said groove, each of said studs extending from the groove in one jaw to the groove in said other jaw; a spring engaging said plunger 40 and adapted to frictionally lock the latter in different positions; and means for clamping said jaws in operative condition, substantially as described.

5. A razor blade holder comprising a pair 45 of hollow handles; coöperating jaws on said handles, there being registering grooves in said jaws; a stationary blade holding stud on one of said handles in the groove thereof; a support on one of said handles; a plunger 50 slidably mounted in said support; a leaf spring in said support and frictionally engaging said plunger; a blade holding stud on said plunger and disposed in the groove of one of said jaws, both of said studs extending from the grooves in one of said jaws into the groove in said other jaw; and means for clamping said jaws in operative condition, substantially as described.

In testimony whereof we have signed our 60 names to this specification in the presence of two subscribing witnesses.

MAURICE WELSH,
ISADORE PAUL.
